7 Claims. (Cl. 40—52)

This invention relates to advertising, indicating and displaying devices. More particularly the invention relates to such devices in which a plurality of frames containing the matter to be displayed are disposed in a cabinet having a display window and adapted to be selectively displaced in the cabinet and raised by depression of a key associated with the cabinet into position behind the display window.

10 In accordance with the principal feature of this invention frames are arranged to one or more sides of the observation window provided in the cabinet and associated with a plurality of buttons or keys corresponding to the frames, each of which buttons or keys is connected with a Bowden wire, lever or the like, movement of which wire, lever or the like serves to bring the selected frame into a condition to be operated by an electric motor and to start the motor.

20 The frames may, if desired, be disposed in two groups on opposite sides of the observation window, preferably above and below, permitting the use of a cabinet of relatively shallow dimensions, and also, if desired, the use of the same guides for the frames of the two groups. Separate guides may, however, be provided for the frames of the two groups.

Various embodiments of the invention are illustrated in the accompanying drawings in which 30 Fig. 1 is a front elevation of the apparatus with the front of the cabinet and the operating keys omitted for the sake of clearness, Fig. 2 is a side elevation, whilst Fig. 3 is a somewhat diagrammatic view to a larger scale showing in detail the switch and frame operating mechanism. Fig. 4 is a diagrammatic illustration of a further embodiment of the invention, while Figs. 5 and 6 are diagrammatic illustrations of a still further embodiment of the invention.

40 Referring to Figs. 1 to 3 of the drawings, 1 denotes a cabinet containing a series of frames 2 and 2' on which is provided the information which it is the function of the particular apparatus to impart. These frames are suitably supported and movable on rotatable spindles and guided in guides. In the form shown each frame is provided at one side with a sleeve 4 embracing a screw-threaded spindle 5, the other side of each frame being mounted in a guide 6. In order to keep the depth of the cabinet within reasonable 45 limits the frames are preferably arranged in two groups, the frames 2 of one group being normally supported above and the frames 2' being supported below the observation window 3. The spindles 5 are mounted in bearings 7 and 8 and are driven

from an electric motor 9 disposed within the cabinet through pulleys 10 and 11 and belt 12, the pulley 11 being mounted on a shaft 13 which drives the vertical spindles 5 through gearing (not shown). The frames are adapted to be moved selectively to bring the information thereon into register with an observation window by means of a series of keys 14 and 14' mounted in a bank at the front of the cabinet 1. Each key 14 connected by means of a Bowden wire or the like 16' to one arm of a bell crank lever 17', the other arm of which engages a slot 18' in a pin 19' which is slidably mounted in the sleeve 4 and on depression of the key moves the bell crank lever against the action of a spring 21'. Each key 14 operates through Bowden wires 16 a bell crank lever 17, the other arm of the bell crank lever 17 engaging a collar 18 on the pin 19 which is normally held in engagement with an annular slot 20 in the screw threads 5 by means of a spring 21. On depression of the keys 14' the keys engage bars 22 mounted on bell crank levers 23 which engage collars 24 on a spindle 25 which operates a bell crank lever 26 connected by link 29 to a switch arm 27 of a mercury switch 28. In the same 20 manner depression of a key 14 serves to operate the mercury switch 28'. The switches 28, 28' are connected in series and control the electric motor 9.

The switch arm 27 is also connected by means of a rod 30 and double-armed lever 31 to a rod 32. A connecting link 33 mounted on the shaft 32 serves to move a pivot 34 mounted at one end of a double-armed lever 35 pivoting about a shaft 36. A cam bar 37 is mounted in the other end of the double-armed lever 35.

The switch 28' is also connected by means of a rod 30', pivoted lever 31' to a shaft 32'. A connecting link 33' mounted on the rod 32' serves to move a pivot 34' mounted in one end of a double-armed lever 35' pivoting about a shaft 36'. A cam bar 37' is mounted in the other end of the double-armed lever 35'.

The cam bars 37, 37' co-operate with cams 39, 39' mounted on the frames 2, 2'.

45 Annular grooves 20, 20' are provided in the screw-threaded spindles 5 to engage with the pins 19, 19' so that the frames 2 and 2' may be held in predetermined positions irrespective of the rotation of the spindles 5. Rubber buffers 40 and 40' are provided to support the upper frames 2 and lower frames 2' in their lowermost position.

In the operation of the apparatus depression of key 14' corresponding to one of the lower frames serves to close switch 28 which is nor- 50 55

mally in the off position and this starts the motor 9. All of the spindles 5 are therefore set in rotation. At the same time the pin 19' operated by the key 14' is pushed into engagement with 5 the screw thread in the spindle 5 and the frame 2' is thus carried vertically upwards until the pin 19' enters the annular groove 20' which is so positioned that in this position of the frame the information displayed on the frame 2' can be seen 10 through the observation window 3. At this instant the cam 39' engages the trip bar 37' which opens the switch 28' thereby stopping the motor 9. The frame 2' remains in its elevated position in front of the window 3 until the key 14' 15 is released when the pin 19' is withdrawn from the annular groove 20' on rod 5 and the frame 2' allowed to drop by gravity to its normal position of rest on the rubber buffer 46'. When the key 14' is released switch 28 is returned to the 20 normal off position while the cam 39 releases the cam bar 37' thus permitting switch 28' to return to the closed position.

Pressure on one of the keys 14 corresponding to one of the upper group of frames opens switch 25 28' which is normally in closed position and also withdraws the pin 19 from the screw thread on the spindle 5 thus allowing the frame 2 to drop into position in front of the observation window 3. As the frame 2 drops the cam 39 trips the 30 cam bar 37 thereof closing switch 28. When the pressure on the key 14 is released switch 28' returns to the normal on position or is closed, thus starting up the motor 9 and rotating the spindles 5 and at the same time pin 19 is allowed to enter the screw thread on the rotating 35 spindle 5 and the frame 2 is raised until the pin 19 engages with the upper annular groove 20 where the frame remains suspended. The cam bar 37 is also released by the cam 39 thus returning switch 28 to its normal off position and 40 stopping the motor 9.

If any two of the keys 14' controlling the lower series of frames should be depressed together the two corresponding frames 2' would be raised into 45 a position before the observation window 3 but of course only the matter contained on the frame nearest the window would be seen. If two keys 14 controlling the upper group of frames were depressed at the same time the two corresponding frames would drop and be restored to normal position on release of the keys.

Depression of any of keys 14 and 14' may also serve to light an electric lamp or lamps for the purpose of illuminating the matter contained on 55 the frame brought into position before the observation window.

In the embodiment illustrated in Fig. 4 of the drawings the frames 2 are arranged in a single group below the window 3, each frame being provided with vertical guides 6. The frames 2 are supported on rubber blocks 48' and each frame 2 is adapted to be raised in front of the observation window by means of a wire, cord or the like 41, attached to the frame 2 and passing over a 60 pulley 42 at the upper end of the cabinet and thence round a corresponding grooved roller or pulley 43 mounted loosely on its axle, the end of the wire being attached to the pulley 43 so that on rotation, the wire 41 is wrapped around the 65 pulley 43 and the frame 2 is raised before the observation window 3. Each roller or pulley 43 is mounted on a pivoted lever 44 which is adapted to be moved into a position to cause the pulley 43 to engage with one of a pair of cylindrical 70 friction rollers 45 which are driven by means of 75

belting 12, 12' from an electric motor 9. Each of the levers 44 is connected by means of a Bowden wire 16 to a corresponding spring controlled key 14.

Attached to each wire 41 is a collar or the like 48 which engages with a bell crank lever 47 connected by means of a link 48 to a mercury switch 28.

The key board is, of course, normally placed at the front of the machine in the position shown 10 in chain dotted lines.

For the lower pair of levers 44 the casing of the Bowden wire 16 is stationary, the wire itself being connected to the pivoted arms 44 at one end and to a double-armed lever 49 at the other end, the lever 49 being operated by the key 14. For the upper pair of levers 44 the inner wire is fixed and the movement is transmitted by the outer casing of the Bowden wire 16.

The mercury switches 28 are normally closed 20 and in series with the main motor switch (not shown). When one of the keys 14 is depressed to bring the corresponding frame into a position before the observation window 3 the main motor switch is closed, thus starting up the electric 25 motor 9 and raising the desired frame. When the frame is raised into a position before the observation window one of the mercury switches 28 is opened by means of the collar 46 on the wire 41 engaging the bell crank lever 47 thus 30 stopping the electric motor 9. Release of the key 14 opens the main motor switch, and on the frame 2 returning to its normal position, the mercury switch 28 is returned to its closed position.

Referring to Figs. 5 and 6 of the drawings the frames 2 are supported in vertical guides 6 below the observation window 4 as described with reference to Fig. 4, each frame being provided with a wire, rope or the like 41 passing over 40 grooved rollers or pulleys 42 at the top of the machine. Each wire 41 is provided with a loop, collar or the like 49 adapted to engage with a corresponding hook or pair of prongs 50 provided on a cylinder 45 which is driven by means 45 of an electric motor 9.

Each of the wires 41 is guided into and out of the path of the rotating cylinder 45 by means of a guide member 51 mounted on a pivoted lever 52 which is adapted to be depressed or raised by 50 means of a Bowden wire 16 connected to a corresponding key 14. Depression of a key 14 serves to pull the inner member of the Bowden wire 16 thus guiding the loop, collar or the like 49 of the corresponding wire 41 into the path of 55 the hooks or prongs 50 on the rotating cylinder 45 and at the same time closing a switch 53 through the pivoted trip bar 54.

When the switch 53 is closed the coil of an electromagnet 55 is energized thus attracting a 60 spring controlled lever 56 which serves to couple the electric motor 9 with the cylinder 45 through the medium of a friction clutch 51. Release of the key 14 opens the switch 53 thus releasing the spring-controlled lever 56 and disconnecting the 65 cylinder 45 from the motor 9. When the cylinder 45 is disconnected from the motor 9 the weight of the frame 2 will rotate the cylinder and release the loop 49 on the wire 41 from the hook 50. It is assumed in this construction that the main motor switch is normally closed and connected in series with the switch 53 so that when the switch 53 is closed the motor is started up.

I claim:

1. A display device comprising a cabinet, an observation window in said cabinet, a plurality of cards containing matter to be displayed mounted laterally of said observation window and movable in said cabinet, a plurality of keys corresponding to the display cards, an electric motor associated with said display cards, a switch for said motor and means connecting each key with 5 said switch and with one of said cards to render the selected card operable by the electric motor.
2. A display device comprising a cabinet, said cabinet formed with a viewing opening, a plurality of screw threaded spindles supported for 10 rotation in said cabinet, a plurality of frames containing matter to be displayed, a nut-forming member connected with each of said frames and engageable with one of said screw-threaded spindles, a plurality of keys, one for each of said display frames, an electric motor for rotating said spindles, switch means for controlling said motor, means connecting each of said keys with said switch means, and means connecting each 15 of said keys with one of the nut-forming members whereby said nut-forming member may be engaged with or released from its spindle.
3. A display device comprising a cabinet, said cabinet provided with a viewing opening, a plurality of screw-threaded spindles mounted laterally of said viewing opening, a plurality of frames containing matter to be displayed, a nut-forming member connected with each of said display frames and engageable with one of said screw-threaded spindles, a plurality of keys mounted in 20 said cabinet, one for each of said display frames, an electric motor for rotatably driving said screw-threaded spindles, switching means for controlling said motor, means connecting each of said keys with the nut-forming member on the corresponding frame, means connecting each key with the switching means and means on said screw-threaded spindles serving to hold the frames in 25 position before the viewing opening or beyond the viewing opening.
4. A display device comprising a cabinet, said cabinet provided with a viewing opening, a plurality of frames containing matter to be displayed, a plurality of keys associated with the display frames, a friction disc associated with each of said frames and each of said keys, a tension member connecting each of said frames with its associated friction disc, an electric motor, a cylinder rotatably driven by said motor, switching means for controlling said motor, including a switch adapted to be closed by depression of any of said keys, and means operated by any of said keys to move its associated friction disc relative to 30 said cylinder whereby to bring said disc and cylinder into driving engagement.
5. A display device comprising a cabinet, said cabinet provided with a viewing opening, a plurality of frames containing matter to be displayed within said cabinet, a plurality of keys mounted in said cabinet, a friction disc associated with each of said frames and each of said keys, a tension member connecting each of said frames with its friction disc for bringing said frame in front of said viewing opening, an electric motor, a cylinder rotatably driven by said motor, a main switch for starting said motor, said switch adapted to be closed by depression of any one of said keys, means operable by any of said keys to bring the corresponding friction disc into engagement with said cylinder whereby to bring the frame in front of the viewing opening, a second switch 35 connected in series with said main switch and means for opening said second switch when said frame is in front of said viewing opening.
6. A display device comprising a cabinet, said cabinet provided with a viewing opening, a plurality of frames containing matter to be displayed within said cabinet, a plurality of keys mounted in said cabinet, one for each of said display frames, a friction disc associated with each of said frames and each of said keys, a tension member connecting each of said frames with its friction disc, said tension member serving to bring said frame in front of said viewing opening on 40 rotation of said friction disc, an electric motor, a cylinder rotatably driven by said motor, a main switch for starting said electric motor, said switch adapted to be closed by the depression of any one of said keys, means operable by each of said keys to bring the corresponding friction disc into driving engagement with said cylinder, said means including a pivoted lever supporting said friction disc, a second switch connected in series with said main switch and means for opening said second switch when said frame is in position before said 45 viewing opening.
7. A display device comprising a cabinet, an observation window in said cabinet, a plurality of frames containing matter to be displayed mounted laterally of said observation window and movable in said cabinet, a plurality of keys mounted in said cabinet corresponding to the display frames, an electric motor associated with said display cards, a rotatable cylinder adapted to be driven by said motor, a switch for starting said motor, a plurality of tension members attached to said display frames and extending into the path of the rotatable cylinder and means on said cylinder serving to engage said tension members and means operated by each key to bring the corresponding 50 tension member into engagement with the last mentioned means on said cylinder whereby to produce operation of the selected frame by the electric motor.

NICHOLAS SANDOR. 60
